[57] CLAIM

The ornamental design for a dispensing port for a container, as shown and described.

DESCRIPTION

FIG. 1 is a top perspective fragmentary view of a dispensing port for a container showing my new design with a portion of a container being shown in broken lines to illustrate environmental use only;

FIG. 2 is a top plan view thereof;

FIG. 3 is a bottom plan view thereof; and,

FIG. 4 is a cross sectional view thereof, taken on line 4—4 of FIG. 2.
